UNITED STATES PATENT OFFICE.

HENRI FELIX MARIE LEMAIRE, OF PARIS, FRANCE.

CHAPELET, CHAIN-PUMP, OR SIMILAR APPARATUS.

SPECIFICATION forming part of Letters Patent No. 629,107, dated July 18, 1899.

Application filed April 16, 1898. Serial No. 677,850. (No model.)

To all whom it may concern:

Be it known that I, HENRI FELIX MARIE LEMAIRE, manufacturer, a citizen of the Republic of France, residing at 152 Rue de Rivoli, Paris, France, have invented certain new and useful Improvements in or Relating to Chapelets, Chain-Pumps, or Similar Apparatus, of which the following is a specification.

This invention relates to a chapelet or chain-pump and apparatus for use in raising water, dredging, or for similar purposes in which a series of pivoted or swinging scoops or buckets is employed; and the invention has important advantages over similar apparatus hitherto known.

In the usual water-raising devices the buckets are secured to the links of the chain, and in order to be emptied they must pass over at least one-fourth of the circumference of the upper roller or drum, or, in other words, their inner faces must come into a horizontal position. It is at least one-fourth of the circumference, because owing to the curvature that water forms in a receptacle rotating about a horizontal axis it is necessary in order to enable a bucket to be completely emptied to cause its inner face to form a downwardly inclined angle with the horizontal line, which obviously requires that the upper bucket should pass at least a quarter of the revolution of the drum. This results in a serious drawback, affecting the efficiency of the apparatus. In fact, as with this description of raising devices it is necessary in order to empty the buckets to raise the water, &c., to a higher level than that at which it is to be received it is advisable to decrease the diameter of the upper drum in order to reduce the height to which the liquid is to be raised; but in that case it is necessary to give it very small speed, otherwise the jet of liquid flowing out of the bucket would pass beyond the receptacle intended to receive it. In order to avoid this drawback, the buckets are pivoted in such manner that at the slightest inclination given to them on passing around the drum they swing or turn over to a sufficient extent to at once pour out all their contents into the receptacle, the result being that the speed of the rotation of the upper drum may be increased without any inconvenience or risk of loss of water.

In the accompanying drawings, Figure 1 is a front elevation of the improved chapelet; Fig. 2, a section on the line 2 2 of Fig. 1; Fig. 3, an elevation of a link with its bucket in its normal position; Fig. 4, a vertical section of the same link, with the bucket turned over; Fig. 5, an elevation of a modified construction of the chapelet; Fig. 6, a vertical cross-section on the line 6 6 of Fig. 5; Fig. 7, a view of a link and bucket of the chapelet shown in Figs. 5 and 6, and Fig. 8 a section of a link on the line 8 8 of Fig. 7.

The chapelet or chain-pump according to the present invention comprises a chain with one kind of link. Each link consists of a metallic frame *a*, the hinged parts of which are formed by the vertical sides folded at a right angle, Figs. 1 to 4. These links are connected by cylindrical pins *b*, recessed in the center to receive a spring *c*, secured to the upper horizontal side of the link. This spring serves to hold the pin *b*, which can thus rotate about its own axis, but cannot move longitudinally. Each link carries a bucket or scoop *d*, the lateral sides or lower lugs *d'* of which are mounted on studs or screws *e*, secured to the folded parts of the vertical sides of the link. Each lug *d'* has a projection which is adapted to engage with the lower horizontal side of the link *a* when the bucket has swung over, said projection and the part *a'* of the link engaged thereby thus forming means for limiting the inward swing of the bucket on its pivot. The bottom of the bucket and the bottom cross-bar of frame *a* are means for limiting movement of the bucket in the opposite direction.

The links *a*, provided with their buckets *d*, are connected by pins *b*, the ends of which project and are adapted to engage with the teeth of two disks *f f*, secured to a spindle *g*, supported in bearings *h h* and caused to rotate by means of a crank *g'* on one of the ends of said spindle or in other desired manner. As soon as, owing to the rotation of the disks *f f* forming the chain-wheel, a link comes into engagement with them, it gradually becomes inclined, and almost immediately the bucket *d*, arriving full of water-pivots about its hinges *e e* and falls over, discharging its contents into a chamber constituted by walls *i i* of galvanized iron arranged between the disks *f f*. The water thence flows

through a pipe or conduit *k* to any desired reservoir or place.

With the pivoted buckets according to the present invention the disks *f* *f* may be rotated at a great speed, as the buckets *d* turn over suddenly and their contents are immediately discharged. Moreover, there is provided a lip or extension *i* in the chamber *i* for catching any projected water that may be shot over, and thus avoiding any loss.

In case a little water passes between the walls *i* *i* and the adjacent disks *f* *f* it can be caught and delivered into the pipe *k* by flanges *i*², surrounding the lower portion of the disks.

When a bucket *d* has made half a revolution on the disks *f* *f*, it comes into a vertical position, but bottom upward, in which position it dips into the water of the well, &c., where it is filled and rises again in an upright position, ready to swing over and empty itself again on arriving at the disks.

When the apparatus is stopped, it is necessary to prevent all the buckets on the ascending side which are full from causing movement of the whole apparatus owing to their weight. This could obviously be effected by means of a ratchet wheel and pawl mounted on the spindle *g*; but to avoid the disagreeable noise caused by the use of such ratchet-gear it is preferable to use the well-known ball or roller clutch, consisting of a ratchet-wheel *m*, mounted at one end of the spindle *g* and adapted to rotate with the shaft in a fixed cup *n*. Between the teeth of the ratchet-wheel are arranged cylindrical rollers, which when the shaft *g* and the ratchet-wheel *m* rotate in the direction indicated by the arrow, Fig. 1, (the direction in which the disks *f* *f* rotate when the chapelet is working,) are caused to rotate by the ratchet-wheel *m* without producing any effect; but if the crank *g*' is released the full buckets tend to rotate the disks *f* *f* in the opposite direction. The ratchet-wheel *m* follows this movement; but the rollers rolling on the inclined faces of the ratchet-teeth become wedged between the latter and the inner face of the cup *n* and prevent the apparatus from rotating.

In the construction shown in Figs. 5 to 8 each link *a* consists of two strips or pieces of flat metal riveted together and forming a fork for the purpose of receiving the corresponding portion of the adjoining link. The pin *b*, connecting together two links, has its central portion of a diameter slightly larger than that of the ends, the opposite end of one of the links to that of the fork being mounted on said central portion. This thickened portion of the pin is held between the two branches of the corresponding fork and prevents the pin from coming out. Each element of the link has, moreover, a bent arm *a*', and on and between these two arms of each link is pivoted a bucket *d*. The bucket can swing on its pivots, the extent being limited by the oblique ends *a*² of the arms *a*', against which rests the

bottom of the bucket when it is swung over. The single disk or drum *f* on which the chain travels is cast or formed with teeth *f*', arranged at regular intervals and projecting laterally. Each tooth is recessed in the center to enable the ends of links *a* to engage therein, and each tooth is also provided with a notch or groove normal to the drum and destined to receive the two branches or ends of the pins *b*. A chamber *i* is, moreover, arranged under the disk *f* to receive water discharged from the buckets *d*, and a branch *l* is connected to a pipe conducting the liquid to the place where it is to be delivered. As in the construction Figs. 1 to 4, the buckets of the second construction swing over almost immediately after the chain has begun to turn on the disk and discharge their contents. This construction is simple and has the advantage of requiring only one disk instead of two. The chain is, moreover, easier to manufacture and the whole apparatus cheaper than the first-described form.

Having now particularly described and ascertained the nature of this invention and in what manner the same is to be performed, I declare that what I claim is—

1. The combination of a chain-supporting wheel, an endless chain consisting of links pivoted together, inwardly-falling buckets the bottoms of which are pivoted to said links, the pivots being so placed as to throw the center of gravity of the ascending buckets slightly outside of their pivots, means preventing said buckets falling outward, a conduit *i* below the part of the chain passing over said wheel and between the ascending and descending parts of the chain, whereby a slight tilting of the links causes the buckets to empty inward.

2. The combination in a chapelet or chain pump apparatus, with a chain supporting and driving wheel, and an endless chain consisting of links with parallel sides, and pivots connecting said links, said pivots being recessed intermediate the sides of the links, and springs *c* secured to the links and engaging the recesses of the pins, of buckets pivoted to said links.

3. The combination of the driving-spindle, disks thereon, a chain having buckets supported and driven by said disks, and said buckets being adapted to empty inward, and a conduit *i* inclosed by the lower part of said disks and into which said buckets empty and inclosing flanges *i*².

4. A chain device for pumps having links each link consisting of a frame *a* with lateral sides at right angles thereto, pins pivoting the links together, buckets having bottom lugs *d*', pivots *e*, said lugs *d*' having projections adapted to engage frames *a* when the buckets turn the desired distance on their pivots.

5. The combination of the driving-shaft, the driving-wheel having disks and teeth *f*' thereon, a chain with buckets supported by

said driving-wheel, said chain having pivot-
pins *b* connecting the links and adapted to
engage said driving-wheel, each link of the
chain consisting of flat plates connected to-
gether and terminating at one end in a fork
which holds the pins *b*, said flat plates having
arms *a'*, and buckets pivoted to said arms.

Signed at Paris, France, this 1st day of April,
1898.
